Clarence S. Applas, INVENTOR,

UNITED STATES PATENT OFFICE.

CLARENCE S. APPLAS, OF SACRAMENTO, CALIFORNIA.

VEHICLE CURTAIN FASTENER.

1,422,513.

Specification of Letters Patent.

Patented July 11, 1922.

Application filed March 10, 1921. Serial No. 451,415.

To all whom it may concern:

Be it known that I, CLARENCE S. APPLAS, a citizen of the United States, residing at Sacramento, in the county of Sacramento 5 and State of California, have invented a new and useful Vehicle Curtain Fastener, of which the following is a specification.

This invention relates to vehicle curtain fasteners.

10 The object is to provide a fastener for vehicle curtains, such as the curtains of automobiles, wherein the locking means carried by the curtain, may be readily placed over the stationary holding means carried by 15 some part of the frame of the top or the body of the vehicle and caused to lock therewith by manipulating a lever, which operation may be easily effected by hand, and, by a reverse movement of said lever, the parts 20 are caused to separate for the purpose of rolling up the curtains in the usual manner.

Another object is to provide a locking means for engagement with the headed end 25 of the holding post for the curtain, which locking means, by reason of its eccentric mounting, may be caused to frictionally bear against the said post to prevent any rattling or relative movement of the co-acting parts and to prevent any accidental loosening of 30 the locking lever.

A further object is to provide locking means for vehicle curtains which may be easily applied around the necessary hole in the curtain without the use of rivets, or 35 screws and which will prevent any tearing of the curtain or material wear of the parts under the more or less rough usage to which the device is subjected during use.

40 A full and complete understanding of the invention may be obtained from a consideration of the following detailed description, taken in connection with the accompanying drawing forming a part of this specification, it being understood that while the 45 drawing shows a practical form of the invention, the latter is not confined to strict conformity therewith, but may be changed and modified, so long as such changes or modifications mark no material departure 50 from the salient features of the invention, as specifically pointed out in the appended claims.

In the drawing in which similar reference characters designate corresponding parts 55 throughout the several figures:—

Figure 1 is a front elevation of the cur-

tain fastener, shown applied to a portion of a curtain, the parts being in locked position;

Figure 2 is a similar view, the parts being 60 shown in un-locked position;

Figure 3 is a rear elevation, the holding post being shown in cross section;

Figure 4 is a vertical sectional view, taken 65 on the line 4—4 of Figure 1;

Figure 5 is a detail sectional view, taken 70 on the line 5—5 of Figure 2.

Referring to the drawing, there is shown 75 a portion of an ordinary vehicle curtain 1 which, at appropriate points adjacent to its border, is provided with suitable openings 2 for the passage of a headed stud or post 3 which may be carried by a portion 4 of the body of the frame of the vehicle top, as the case may be.

Arranged upon the front and the rear 80 sides of the curtain 1, and in surrounding relation to the opening 2 therein, are similar plates 5 and 6 respectively, having substantially at their center alined openings 7 85 preferably of equal area to the opening 2 in the curtain, all of the openings being of a diameter somewhat greater than the diameter of the post 3, and of sufficient size to permit the passage of the head 8 of the 90 post, as clearly shown in Figure 4 of the drawing.

The front and rear plates 5 and 6, which 95 are identical in form and construction and preferably of general rectangular formation, being square at the bottom and side edges with the top edge of semi-circular contour, and the same may be formed of brass, nickel or some other non-corrosive sheet metal. At the lower corners, which 100 are rounded as shown, and at spaced, opposite points around the upper semi-circular portion of each of the plates 5 and 6, slits 9 are provided in spaced relation to the adjacent edges, though the said slits may be otherwise arranged.

A plate 9^a of similar contour to the front and rear plates 5 and 6, though of somewhat smaller dimensions and having a continuous, marginal flange 10 extending around its entire periphery, is adapted to be placed against the outer face of the outer plate 5 and to be centrally located thereon with the free edge of the said flange 10 bearing against the plate 5. Tongues 11 formed integrally with the flanged plate 9^a are so located thereon as to be in position to pass 105 110

through the aforesaid slits 9 in the front and rear plates 5 and 6, the said tongues being bent over, as shown, to hold the several plates together in position on the curtain.

5 The raised flanged plate 9^a is provided with a centrally located opening 12 in registering relation to the several openings in the plates 5 and 6 and the curtain 1 and of equal diameter therewith so as to permit the passage of the enlarged head 8 of the post 3, as clearly illustrated in Figure 4 of the drawing.

10 Mounted upon the outer face of the elevated plate 9^a and directly over the opening 12, is an eccentrically pivoted button or disc 13, whose periphery normally overrides the said opening 12, the pivot 14 thereof being in the form of a rivet having its inner end headed over against the inner face of the 15 raised plate 9^a and located directly above the center of the opening 12. The disc 13 is provided with an operating arm 15 extending outwardly from the center thereof and in radial relation thereto, the said arm terminating in an inwardly-turned extension 16 which is adapted to strike against the aforesaid flange 10 of the elevated plate 9^a, at the right or the left, as the button or disc 20 is turned about its axis.

25 30 At right angles to the operating arm 15, the periphery of the disc 13 is provided with a cut-out portion 17 struck on a curve coinciding with the curvature of the opening 12, though of slightly greater radius than the same, and this cut-out 17 is located in that 35 portion of the eccentric disc having the smaller radius, so that, when the operating arm 15 is swung to the right, as viewed in Figure 1, the cut-out 17 is located at the top 40 thereof and the increasing diameter of the said disc is acting upon the upper side of the post 3, after the same has been introduced through the several openings aforesaid to crowd the post downwardly against the bottom of the openings, whereupon the head 8 of the post will effectually prevent the disengagement of the curtain from its locked 45 position upon said post.

By turning the disc 13, as indicated in

Figure 2 of the drawing, until the inwardly turned extension 16 strikes the flange on that side of the device, the cut out portion 17 is brought into registering relation with the openings in the several plates and the curtain, whereupon the headed post may be 50 freely withdrawn from its locked engagement with the post.

55 In practice, the fastening device should be placed on the curtain so that the locking button or disc points toward the center of the curtain, for the curtain always draws from the center. This arrangement relieves the locking device from strain and permits it to perform its only function of keeping the fastener on the post.

60 65 By forming the post of sufficient length, as illustrated in Figure 4, one or more of such fastening devices, carried by as many curtains may be secured to a single post.

70 From the foregoing it will be seen that an extremely simple and cheaply manufactured fastening device for automobile or other curtains has been provided, which may be easily operated to lock or unlock said curtain, having no intricate springs or mechanism to become worn or deranged, the operating means being always in view and within reach to simplify said operation.

75 80 What is claimed is:

In combination with a headed post or stud secured to a fixed part, a flanged plate secured to a movable part and provided with an opening for the passage of said post, a disk pivoted on the flanged plate and provided with an operating arm for rotating the disk, said disk having its peripheral edge normally engaging the post to prevent separation of the flanged plate from the post, and having a cut-out portion adapted to align with the post to permit separation of the parts, the free end of the operating arm engaging the flanged portion of the plate for either locking the disk in engaging or releasing position with the post.

85 90 95 In testimony that I claim the foregoing as my own I have hereto affixed my signature.

CLARENCE S. APPLAS.
